UNITED STATES PATENT OFFICE.

FREDERICK W. NEUMAYER, OF BALTIMORE, MARYLAND.

TYPE-LINE-CASTING MACHINE.

Application filed August 26, 1921. Serial No. 495,483.

To all whom it may concern:

Be it known that FREDERICK W. NEUMAYER, a citizen of the United States, residing at Baltimore, in the State of Maryland, has invented certain new and useful Improvements in Type-Line-Casting Machines, of which the following is a specification.

This invention relates to linotype machines and has special reference to the assembling elevator of line casting machines and the principal object of the present invention is to so improve what may be termed the matrix positioning mechanism that all requirements of operation will be fully met.

Another important object of the invention is to provide an improved and simplified mechanism wherein a single finger lever may be used for operating a matrix positioning gate and for operating a matrix supporting ledge or rail.

A further important object of the invention is to provide an improved form of operating mechanism for the gate and rail above referred to wherein the operation of the rail can only be effected with the gate in a predetermined position.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:

Fig. 1 is a front elevation of the assembling elevator of a line casting machine equipped with the improved position controlling device forming the subject of this invention, certain covers or housings being removed to disclose the operating parts.

Fig. 2 is a plan view thereof.

Fig. 3 is a detail elevation of part of the assembling elevator showing the operating parts in second position.

Fig. 4 is a plan view with the matrix positioning parts arranged as Fig. 3.

Fig. 5 is an exploded or disassembled view of the gate and matrix supporting ledge or rail.

Fig. 6 is a section on the line 6—6 of Fig. 5 showing the parts assembled.

Fig. 7 is a side elevation of the assembling elevator and the matrix positioning device.

Fig. 8 is a section on the line 8—8 of Fig. 1.

Fig. 9 is a section on the line 9—9 of Fig. 1.

Fig. 10 is a section on the line 10—10 of Fig. 1.

Fig. 11 is a perspective view showing in detail a slide forming part of the position controlling mechanism.

Fig. 12 is a perspective view showing in detail a latch forming part of such mechanism.

Fig. 13 is a section on the line 13—13 of Fig. 1 showing the parts in one position in full lines and in a second position in dotted lines.

Fig. 14 is a perspective view of the upper part of the matrix positioning mechanism shown in relation to the assembling elevator, the latter being disclosed in dotted lines.

Fig. 15 is a section on the line 15—15 of Fig. 1.

Fig. 16 is a detail section on the line 16—16 of Fig. 7.

Fig. 17 is a perspective view of the parts shown in elevation in Fig. 16.

In the embodiment of the invention herein illustrated there is provided the usual assembling elevator 20 at the top of which is a channel 21 for the reception of matrices M each having an upper matrix die m and a lower matrix die m' . At the bottom of the elevator channel are fixed ribs or rails 22 wherein the bottom ears m^2 of the matrix may rest when it is desired to have the upper matrix die m of each matrix in line casting position. This channel is also provided with the usual spring operated retaining hooks 24 and in the front wall of the channel there is a slot or opening 25 in which is mounted a plate 26 having an edge 27 projectable into the channel so as to form an upper rail on which a bottom ear m^2 of each matrix M may rest when it is desired to have the lower character matrix die m' in alignment for casting.

At the right hand end of this blade 26 the edge 27 is cut back or notched as at 28, and the under side of this portion is bevelled as at 29 to receive the bevelled end 30 of a longitudinal extension or gate. It will be noted by reference to Fig. 6 that the upper surfaces of the edge 27 and of the gate lie in the same plane. This gate is continued to the right from the bevelled portion as shown at 31 and terminates in an upstanding hook or lip 32. The right front portion of the blade 26 is provided with an extension 33 and up-

standing lugs 34 are provided at opposite ends of said extension. One of these lugs, preferably that to the right, is provided with a screw threaded opening 35 while the other lug has a plain opening 36 so that a pin 37 can be passed through the opening 36 and screwed into the opening 35. The gate has a forwardly extending portion 38 terminating at the front in an upstanding flange 39 and aligned eyes 40 are provided through which the pin 37 passes. By this means the gate can slide longitudinally of the blade or rail 26.

Depending from the upper front faces of the assembling elevator is a plate 41 and on this plate is mounted a block 42 from which projects a stud screw 43 having one end of a rocker or lug 44 pivoted thereto. This rocker carries an arm 45 which is connected to the rocker by a screw passing through a slot 46 so that the arm can be adjusted longitudinally of said rocker. Projecting from the arm 45 is a finger 47 which engages a slot 48 formed in the flange 39 of the gate member. Projecting from the rocker 44 is a lug 78 to which is connected the upper end of a link 49. The lower end of this link is suitably guided for vertical movement and carries a pin 50 which projects through a slot 51 in the lower end of the plate 41. Carried by the plate 41 adjacent its upper end is a pin 52 and a coil tension spring 53 connects the pins 50 and 52 and serves to urge the link upward. The plate 41 also carries a main pivot pin 54 wherein is pivoted a brake slide 55 which is held pressed toward the plate 41 by means of a coil spring 56 surrounding the pin 54 and having adjusting nuts 57 on its head. Pivoted on the pin 54 is a latch member 58 having a latch tooth 59 adjacent its lower end. Beneath the slide 55 is also mounted an operating lever 60 having a finger piece 61 on its lower end.

This operating lever is slotted to straddle the latch member 58 and is provided with a lug 61 engageable, when the operating lever is drawn down, with the latch tooth 59. It will now be observed that by moving the finger piece 61 to one side or the other latch member 58 will be correspondingly swung. To the lower end of this latch member is pivoted the upper end of a link 62 which has its lower end bifurcated as at 63 to straddle the pin 50.

When the finger piece 61 is moved to the left the latch member and link 63 forms an elbow joint which is straightened by the movement of the finger piece 61 to the right. This straightening forces the lower end of the link 62 downward and consequently moves the link 49 downward against the tension of the spring 53. This results in moving the lug 44 to the right and consequently moves the gate in the same direc-

tion. Upon movement of the finger piece 61 to the left the latch 49 will rise under the influence of the spring and the gate will move toward the left or open.

Mounted in ears 64 on the upper part of the plate 41 is a rocker plate 65 having upwardly extending fingers 66 which engage in notches 67 formed in the side walls of slots 68 cut in the front edge of the plate or rail 26. Thus when the rocker plate 65 is rocked forwardly the plate or rail 26 is in like manner drawn forwardly and its edge 27 disappears in the slot 25 thus leaving the upper part of the channel unobstructed.

The upper end of the lever 60 is provided with a lug 69 and to this lug is pivoted the lower end of a link 70 which has in its upper end a cam slot 71 wherein engages a pin 72 projecting laterally from an arm 73 depending from the rocker plate 65.

With this construction in mind and noting the form of the cam slot as shown in Fig. 7 it will be seen that as the finger piece 61 is lifted against the action of the spring 56 until the lug 61 is clear of the tooth 59 the lever 60 may be pushed upward. When this is done the pin 72 is forced to the right of Fig. 7 with the consequence that the fingers 66 act on the plate or rail 26 to draw the same forward. Correspondingly downward movement of the lever 60 forces the plate 26 out into the assembling channel. On the plate 41 is a lug 74 which is engaged by the upper end of the lever 60 whenever the finger piece 61 is in position to the right and it is not until this finger piece is in position to the left that the lever 60 can be moved upward to retract the plate or rail 26. Consequently it is only when the gate is in position to the left or open that the plate or rail 26 can be moved laterally into projected or retracted position.

Covering the various moving parts are suitable housings.

In order to understand the complete operation of the device let us assume that the lower rails or ledges which are permanently positioned in the elevator are those on which the matrices rest when the upper dies are aligned for casting while the auxiliary rail 26 is that on which the matrices rest when the lower letters or dies are in alignment for casting. As the matrices are fed down from the magazine the usual star wheel forces them one by one into the assembling elevator.

If during the operation of composition, the operator desires to set up a portion of a line or one or more lines in display, as soon as he reaches the point where the display matter is to begin, he will move the finger lever to the right, thereby projecting the edge 27 of the plate 26 into the elevator channel and providing an upper ledge on which the bottom ears m^2 , of the matrices

for the display, may rest, instead of on the lower ribs or rails 22. The operator then proceeds to actuate the keys of the keyboard for the selection of the desired characters for the display matter and will continue to do so until all the characters for such display are assembled. If a line is completed before the display matter is entirely set up, the operations of the elevator 10 will be carried on in the usual way and the matrices transferred from the assembling to the casting position precisely as before. When the display matter has been completely set up however, the finger lever will 15 be shifted to the left or returned to the normal position whereupon the matrices then assembled will be supported on the lower fixed rails.

Having thus described the invention, what 20 is claimed as new, is:—

1. In a device of the kind described having an assembling channel provided with a matrix supporting rail, an auxiliary matrix supporting rail movable laterally for projection into and retraction out of the channel, an extension on said auxiliary rail forming a gate and movable longitudinally thereof to increase and decrease the effective supporting length of said auxiliary rail, a 25 finger lever mounted for pivotal and sliding movement, a connection between said lever and the extension arranged to shift said extension longitudinally of the auxiliary rail upon pivotal movement of the lever, and a 30 connection between the lever and auxiliary rail arranged to move the rail laterally upon sliding movement of the lever.

2. In a device of the kind described having an assembling channel provided with a 40 matrix supporting rail, an auxiliary matrix supporting rail movable laterally for projection into and retraction out of the channel, an extension on the rail forming a gate and movable laterally therewith and movable longitudinally thereof to selectively increase and decrease the effective supporting length of said auxiliary rail, a finger lever mounted for pivotal and sliding movement, a connection between said lever and the extension arranged to shift said extension longitudinally of the auxiliary rail upon pivotal movement of the lever, a connection 45 between the lever and auxiliary rail arranged to move the rail laterally upon sliding movement of the lever.

3. In a device of the kind described having an assembling channel provided with a matrix supporting rail, an auxiliary matrix supporting rail movable laterally for projection into and retraction out of the channel, an extension on said auxiliary rail, forming a gate and movable longitudinally thereof to increase and decrease the effective supporting length of said auxiliary rail, a 50 finger lever mounted for pivotal and sliding

movement, a connection between said lever and the extension arranged to shift said extension longitudinally of the auxiliary rail upon pivotal movement of the lever, a connection between the lever and auxiliary rail 70 arranged to move the rail laterally upon sliding movement of the lever, and latch means to yieldably hold the finger lever against sliding movement.

4. In a device of the kind described having an assembling channel provided with a matrix supporting rail, an auxiliary matrix supporting rail movable laterally for projection into and retraction out of the channel, an extension on the rail forming a gate and movable laterally therewith and movable longitudinally thereof to selectively increase and decrease the effective supporting length of said auxiliary rail, a finger lever mounted for pivotal and sliding movement, a connection between said lever and the extension arranged to shift said extension longitudinally of the auxiliary rail upon pivotal movement of the lever, a connection 75 between the lever and auxiliary rail arranged to move the rail laterally upon sliding movement of the lever, latch means to yieldably hold the finger lever against sliding movement.

5. In a device of the kind described having an assembling channel provided with a matrix supporting rail, an auxiliary matrix supporting rail movable laterally for projection into and retraction out of the channel, an extension on said auxiliary rail forming a gate and movable longitudinally thereof to increase and decrease the effective supporting length of said auxiliary rail, a finger lever mounted for pivotal and sliding movement, a connection between said lever and the extension arranged to shift said extension longitudinally of the auxiliary rail upon pivotal movement of the lever, a connection between the lever and auxiliary rail 90 arranged to move the rail laterally upon sliding movement of the lever, latch means to yieldably hold the finger lever against sliding movement.

6. In a device of the kind described having an assembling channel provided with a matrix supporting rail, an auxiliary matrix supporting rail movable laterally for projection into and retraction out of the channel, an extension on the rail forming a gate and movable laterally therewith and movable longitudinally thereof to selectively increase and decrease the effective supporting length of said auxiliary rail, a finger lever mounted for pivotal and sliding movement, a connection between said lever and the extension arranged to shift said extension longitudinally of the auxiliary rail upon pivotal movement of the lever, a connection between the lever and auxiliary rail 95 arranged to move the rail laterally upon sliding movement of the lever, latch means to yieldably hold the finger lever against sliding movement, and a positive stop positioned in the path of the sliding movement of the lever to prevent such movement with the extension in extended position.

7. In a device of the kind described having an assembling channel provided with a matrix supporting rail, an auxiliary matrix supporting rail movable laterally for projection into and retraction out of the channel, an extension on the rail forming a gate and movable laterally therewith and movable longitudinally thereof to selectively increase and decrease the effective supporting length of said auxiliary rail, a finger lever mounted for pivotal and sliding movement, a connection between said lever and the extension arranged to shift said extension 100 longitudinally of the auxiliary rail upon pivotal movement of the lever, a connection between the lever and auxiliary rail arranged to move the rail laterally upon sliding movement of the lever, latch means to yieldably hold the finger lever against sliding movement, and a positive stop positioned in the path of the sliding movement of the lever to prevent such movement with the extension in extended position.

- 5 pivotal movement of the lever, and a connection between the lever and auxiliary rail arranged to move the rail laterally upon sliding movement of the lever, latch means to 5 yieldably hold the finger lever against sliding movement, and a positive stop positioned in the path of the sliding movement of the lever to prevent such movement with the extension in extended position.
- 10 7. In a device of the kind described having an assembling channel provided with a matrix supporting rail, an auxiliary matrix supporting rail movable laterally for projection into and retraction out of the channel, an 15 extension on said auxiliary rail forming a gate and movable longitudinally thereof to increase and decrease the effective supporting length of said auxiliary rail and an upstanding lip on the end of the extension to 20 engage and move the matrices received by the extension longitudinally of the channel upon retractive movement of the extension. 8. In a device of the kind described having an assembling channel provided with a matrix supporting rail, an auxiliary matrix supporting rail movable laterally for projection into and retraction out of the channel, an extension on the rail forming a gate and movable laterally therewith and movable longitudinally thereof to selectively increase and 30 decrease the effective supporting length of said auxiliary rail, an upstanding lip on the end of the extension to engage and move the matrices received by the extension longitudinally of the channel upon retractive movement of the extension and means controlled by the operator for regulating the positions of the auxiliary rail and its extension. 9. In a device of the kind described having an assembling channel provided with a matrix supporting rail, an auxiliary matrix supporting rail movable laterally for projection into and retraction out of the channel, an extension on the rail forming a gate and 40 movable laterally therewith and movable longitudinally thereof to selectively increase and decrease the effective supporting length of said auxiliary rail, an upstanding lip on the end of the extension to engage and move the matrices received by the extension longitudinally of the channel upon retractive movement of the extension and a single operating means connected to the auxiliary rail and its extension and movable to vary the positions 45 of the rail and its extension with respect to the channel and the position of the extension with respect to the auxiliary rail.
10. In a device of the kind described having an assembling channel provided with a matrix supporting rail, an auxiliary matrix supporting rail movable laterally for projection into and retraction out of the channel, an extension on the rail forming a gate and movable laterally therewith and movable longitudinally thereof to selectively increase and decrease the effective supporting length of 50 said auxiliary rail, an upstanding lip on the end of the extension to engage and move the matrices received by the extension longitudinally of the channel upon retractive movement of the extension, a finger lever mounted for pivotal and sliding movement, a connection between said lever and the extension arranged to shift said extension longitudinally of the auxiliary rail upon pivotal movement of the lever, a connection between the lever and auxiliary rail arranged to move the rail laterally upon sliding movement of the lever. 11. In a device of the kind described having an assembling channel provided with a matrix supporting rail, an auxiliary matrix supporting rail movable laterally for projection into and retraction out of the channel, an extension on the rail forming a gate and 55 movable laterally therewith and movable longitudinally thereof to selectively increase and decrease the effective supporting length of said auxiliary rail, an upstanding lip on the end of the extension to engage and move the matrices received by the extension longitudinally of the channel upon retractive movement of the extension, latch means to yieldably hold the finger lever against sliding movement. 12. In a device of the kind described having an assembling channel provided with a matrix supporting rail, an auxiliary matrix supporting rail movable laterally for projection into and retraction out of the channel, an extension on the rail forming a gate and 60 movable laterally therewith and movable longitudinally thereof to selectively increase and decrease the effective supporting length of said auxiliary rail, an upstanding lip on the end of the extension to engage and move the matrices received by the extension longitudinally of the channel upon retractive movement of the extension, and a positive stop positioned in the path of the sliding movement of the lever to prevent such movement with the extension in extended position.

In testimony whereof I affix my signature:

FREDERICK W. NEUMAYER.
